VERTICALLY STRINGED GRAND PIANO

Alexander P. Brown, Beechhurst, N. Y.

Application June 7, 1947, Serial No. 753,186

11 Claims. (Cl. 84—240)

1

It is well known in the art of the grand pianos that they take up too much floor space in the average home. Reason for this is that the strings are stretched horizontally on a horizontal plate.

In order to save floor space in the modern small homes, a grand piano is provided with a vertical plate, and the strings are stretched vertically, thus saving much floor space in this new type of piano.

The invention provides a standard height small grand piano with vertically stringed plate improved to accommodate longer bass strings, contrary to the construction heretofore employed. The bridge of the bass strings is placed near the tuning pins instead of the loop end of the bass strings.

The invention provides an increase in the sounding board area for the bass bridge area by decreasing the bass side of the wrest plank or tuning pin block.

The invention provides a grand piano with a demountable slip or skirt to cover the under cut bottom portion of the vertical plate, strings, sound board and back. A frameless demountable front bottom board with pedal cut outs may be also used. This insures accessibility for the piano technicians to repair, clean or re-decorate to any color scheme of a home.

The invention will be more fully described hereinafter, embodiments thereof shown in the drawings, and the invention will be finally pointed out in the claims.

In the accompanying drawings,

Fig. 1 is a vertical central section of an average height grand piano of the compound rounded rim case type, having the improved case, plate, and undercut sounding board embodied therein;

Fig. 2 is a front view of the improved plate with bridges and soundboard behind the same;

Fig. 3 is a detail section taken on line 3—3 of Fig. 2;

Fig. 4 is a detail section taken on line 4—4 of Fig. 2;

Fig. 5 is a front view of the soundboard and pin block with frame removed and showing the bass bridge directly on the soundboard, and the treble bridge extended to the lower corner and supported by a footing, the dotted lines indicating the rear back framing posts;

Fig. 6 is a detail section taken on line 6—6 of Fig. 5;

Fig. 7 is a detail section taken on line 7—7 of Fig. 5;

Fig. 8 is a plan view partly in section of the empty case, with keyboard, pedals, plate, sound-

2

board, the back framing posts, and case fastening flanges shown therein;

Fig. 9 is a horizontal section of the lower part of the undercut portion;

Fig. 10 is a plan view of the demountable cover or skirt;

Fig. 11 is a front view of the same;

Fig. 12 is a section taken on line 12—12 of Fig. 2; and

Fig. 13 is a section taken on line 13—13 of Fig. 2.

Similar characters of reference indicate corresponding parts throughout the various views.

Referring to the drawings, and more particularly to Figs. 2 to 7, the plate 10 made of cast iron or the like in the manner well known, consists of a body portion 11 and lateral extensions 12 and 13, at the upper part thereof. At the front part 20 of the frame 10, ribs or upright flanges 15 are provided to strengthen the plate in the manner well known. To lighten the frame, openings 16 are provided as known.

The improvement consists in providing a reinforcing member 20 substantially parallel with the rib or flange 15 at the left hand side of the frame, so that a strengthening member is provided at each side of the plurality of bass strings 21 to resist the strain of the strings.

The upper part of the plate 10 has an opening 16 increased in size to enable a bridge 23 to pass therethrough, which bridge is secured to the upper part of the soundboard 25. The bridge 23 has a rib 24 with guide pins 26 thereon for the strings 21. The bridge 23 with openings 23b (which may be omitted) is supported on the footing 23a, as shown in Fig. 7. The footing 23a extends under the plate. The soundboard 25 has a body portion 25a and lateral portions 25b and 25c. By extending the soundboard by means of the lateral extensions 25b, and extending the plate accordingly, an increased size of sounding board is provided and the location of the bass bridge 23 made possible, together with the arrangement of the tuning pins 45, and string pressure resistance bar 43, all at the upper end of the soundboard.

The soundboard 25 also supports the treble bridge 27 for the treble and mid section strings, and the bridge 27 extends downwards to the lowest left hand part of the soundboard as practical to convey the vibrations towards the central part of the soundboard, that is, to bring the vibrations away from the edge of the soundboard. The lowest portion of the mid bridge 27 is supported by a bridge member 28 on a footing 31 secured to the

soundboard 25. The lower end portion of the bridge 27 extends from its end 30 to the footing 31 and is spaced from the soundboard, the portion from 30 to 31 being inclined to the soundboard.

A wrest plank or pin block 33 is of angular shape, the smaller or bass end 33a fitting into the space 34 between the flanges 35 of the plate 10 (Fig. 12). These flanges 35 act as a re-inforcement to the plate. The wider part or treble end 36 fits into the space 34a between the reinforcing flanges 35a of the plate 10 (Fig. 13). These flanges extend along the rear of the plate from end to end. The upper part of the soundboard abuts against the lower flange as seen in Fig. 1, and seats on an extension 36.

At the upper part of the plate 10 and at each side thereof, the reinforcing flanges 55 (Fig. 8) are integral with the plate, and have openings 56 for the passage of fastening screws 57, to secure the plate to the casing 60 (Figs. 1, 12, and 13).

The rear of the soundboard has strengthening ribs 37 as known (Fig. 1). The dotted lines in Fig. 5 indicate back framing posts 38, as known (see also Figs. 8 and 9). Reinforcing beams 39 connect the posts 38.

The bass strings 21 are secured to hitch pins 40 (Fig. 1) arranged partly on the lower surface of the frame and partly on the bottom edge of the plate. Approximately one third of the bass strings extend below the plate. From the hitch pins 40 the strings 21 pass over a pressure resistance bar 41 guided by pins 42, and then extend upwardly over a pressure resistance bar 24 of the bridge guided by pins 26, (Figs. 1 and 2) and then over the plate pressure resistance bar 43 having guide pins 44 and then to the tuning pins 45.

The left portion of the midsection strings 46 pass over the spaced portion of the bridge 27, guided by pins 47, and up to the pressure resistance bar 48. The treble strings 49 are arranged and secured in the well known manner.

By arranging the lowest group of the bass string, hitch pins 40 at the bottom edge of the plate 10, and the plate pressure resistance bar 41 at the lowest possible position of the plate, and placing the bridge 23 with its pressure resistance bar 24 at the highest possible position at the top of the plate, the vibration lengths of the strings are longer than when used as heretofore. This is of importance since in this piano plate the effective part of the strings are longer than heretofore, for the same size plate, and thereby give a better bass tone.

The re-inforcing members 15 and 20 being arranged parallel with the direction of the bass strings 21, and one at each side of the same, give strength to the plate and resist the forces created by the tensioned bass strings. As the improved frame is shorter laterally than the usual frame to enable the piano to be narrower, and as the plate has openings near the lateral edges, these strengthening flanges 55 are important. The reinforcing flanges 55 serve to strengthen the upper two ends of the plate 10.

The improved plate and soundboard are shown as applied to a piano in Fig. 1. The soundboard 25 is secured to the crownframe 59, which is secured to the back 39 as known. A reinforcing beam 51 is provided. Bolts 52 join the plate 10, to a reinforcing plate 54 seated in the reinforcing member 51.

The piano case 60 is supported by legs 58, provided with vibration absorption means 59. The

embodiment utilizes three legs, namely, two front legs and one rear leg, only two being shown.

Space saving latch pedals 61 operate in the usual manner, but are in the embodiment of very simple construction. It requires only two bolts 65 for pinioning and securing three pedals into the piano. Heretofore a set of three pedals required three pins, four pinion blocks and eight screws to give the same results.

The vertically disposed plate 10 with the soundboard 25, divides the upper case 60 into two parts, the front part A and the rear part B.

The front part A is enclosed by a perforated top 63, on which a music desk 64 is arranged, by a frontboard 66, by a cover or fallboard 66a, by a front wall 67 and by a key-bed 68. A piano cover 70 is hinged at 71 to the left of the bass side of the case.

Within the front part A are the keys 76, the piano actions 77, a touch control 78, a damper mechanism 79, and key frame rails 76a and 80. One touch control 78 at one side of the case is for the treble, and one is at the other side of the case for the bass.

The piano actions 77 may be easily taken out separate from the damper mechanism 79. The structures of the piano actions shown are more particularly described and shown in my copending application Serial No. 703,969 filed October 18, 1946, reference to which is hereby made.

The keys 76 and the key frame rails 76a and 80, with the actions 77, all of them may be slidably taken out as a unit, by removing the front board 66. The front wall 66b is attached to the keyboard.

Below the keyboard 80 is a space, and this is utilized for a sheet music container or drawer 82, which may be moved out of the front of the case, the front 83 of the container 82 forming a part of the front of the piano. This drawer may be separately moved out.

The space A forms a sound mixing or acoustic chamber.

The rear part B, extends rearwardly of the soundboard and forms a resonance space as described and shown in my applications Serial No. 654,116 and Serial No. 654,117, filed March 13, 1946, now abandoned, of which this application is a continuation in part, and such space cooperates in vibratory resonance with the space A in the casing formed by frontboard 66, mid-top 63, with openings 63a and walls of the casing 60. The bottom 87 of the rear part B may be open or closed, and the top 81 may be provided with openings 81a, free to the atmosphere when the cover 70 is up.

The upper parts of the plate, and soundboard, and in the embodiment the upper part of the frame, extend from side to side of the piano case and divide the case into a forward sound resonance chamber and a rearward resonance chamber. The vertical casing is intermediate or between the front and rear of the piano case, longitudinally considered, and also transversely considered. The vertical resonance chamber at the rear of the soundboard in the vertical casing, forms an inverted L shape with the rear resonance chamber of the horizontal piano case, these vertical and horizontal resonance chambers being in communication with each other. The interior of the vertical casing at the front of the soundboard of the vertical casing communicates with the horizontal resonance chamber in the piano case at the front of the soundboard. The two horizontal resonance chambers of the piano case

are horizontally in line with the parts of the strings struck by the hammers.

The case 60 is preferably made of plywood as known and as shown.

The part B rearwardly of the plate 60 extends to conform to the width of the soundboard laterally, and the configuration of the case may vary rearwardly thereof.

Below the upper case, a vertical downwardly extending back frame 90 is provided (Fig. 9). The improvement here is a demountable skirt. For this purpose, the frameless front bottom board 91 with pedal cutouts 61a has its sides provided with grooves 92, at its inner surface. Before this bottom frontboard 91 is applied, the skirt 93 is placed in position. This skirt 93 consists of a larger portion 94 of angular shape having a sidewall 95 having a flange 99, to be seated and secured by screws 97 through the slots 99a to the front of the upright 90. To the larger portion 94, a smaller portion 98 is hinged. A flange 99 is also on the smaller side portion 98, to be seated on and secured by screws 97 through the slots 99a to the front of the upright 90a. The pivoting at 93a of this part 98 facilitates the attachment. The front bottom board 91 is then applied with the suitable cutouts 61a over and along the sides of the pedals and by having its lower end grooved at 91a it is engaged by a flat piece angle bracket 91b (Fig. 1). The upper part of the front bottom board 91 is held by a spring 91c secured to the keybed 68. The skirt may be of metal suitably decorated or of plastic. The color of the skirt may be in conformity with the color scheme of the room. This demountable skirt facilitates access to the lower part of the piano.

I have described several forms of my invention, but obviously various changes may be made in the details disclosed without departing from the spirit of the invention as set out in the following claims:

I claim:

1. In a piano, the combination of a case of grand piano configuration, a vertically disposed soundboard, a vertically disposed string plate connected with the soundboard, a vertically disposed back frame parallel with and secured to said soundboard, and extending below the grand piano case, the upper parts of the frame, plate and soundboard extending from side to side of said case and dividing the grand piano case into a forward sound resonance chamber and a rearward sound resonance chamber, and a vertically disposed casing enclosing the parts extending below the grand piano case, said last named casing being intermediate the front and rear of the grand piano case.

2. In a piano, the combination of a case of grand piano configuration, a vertically disposed soundboard, a vertically disposed string plate connected with the soundboard, a vertically disposed back frame parallel with and secured to said soundboard, said plate, soundboard and frame extending below the grand piano case, the upper parts thereof extending from side to side of said case dividing the case into a forward sound resonance chamber, and a rear resonance chamber, and a vertically disposed casing enclosing the parts extending below the grand piano case, said soundboard, plate and frame being undercut in the parts extending below the grand piano case, said last named casing being intermediate the front and rear of the grand piano case.

3. In a piano, a vertically disposed lower casing, said casing having a front bottom board, and a detachable skirt, said skirt having an angular major member forming the rear of the casing and one side forming the side of the casing, and a minor part hinged to the major part forming the other side of the casing.

4. In a piano, a vertically disposed lower casing, said casing having a front bottom board, and a detachable skirt, said skirt having an angular major member forming the rear of the casing and one side forming the side of the casing, and a minor part hinged to the major part forming the other side of the casing, said front bottom board being frameless and having cutouts for the pedals.

5. In a piano, a vertically disposed casing, said casing having a front bottom board, and a detachable skirt, said skirt having an angular major member forming the rear of the casing and one side forming the side of the casing, and a minor part hinged to the major part forming the other side of the casing, both of said sides having flanges with openings for the passage of screws, for detachably securing the skirt to the front bottom board.

6. In a piano, a string plate, and undercut soundboard, an undercut back with posts and re-enforcement bolt plate, a wedge shaped pinblock on the back and above the soundboard, flanges extending from the plate on the side front of the soundboard to strengthen the plate, said flanges extending along the top of the plate and partially along the upper side of the plate, said lateral flanges having openings for screws to attach the flanges to a rim or upper casing of the piano, and said plate having rear snugly fitting flanges extending from it over the wedge shaped pinblock, having bolts to secure the plate down over the soundboard to said back post frame.

7. In a piano having strings, a string plate having an opening and tuning pins at the upper right end, a soundboard parallel with the plate, a footing on the soundboard at its lower left end, a bridge for the midsection strings on the footing and extending through the string plate opening, an intermediate inclined member on the footing and supporting the lower left end of the midsection bridge in an inclined position and guide pins for the strings in the bridge.

8. In a piano, a string plate having a horizontal flange extending across the string plate at its upper rear portion, and a second flange at the rear of the plate extending across the string plate and inclined to the first flange, a soundboard parallel with the string plate, and terminating at its upper end below and contiguous to the inclined flange and having an inclined end parallel with the inclined flange, a back post frame, and a wedge shaped pinblock above the soundboard, and embraced by the said flanges of the rear side of the plate and secured to the back post frame.

9. In a piano, an undercut string plate, an undercut soundboard, an undercut back with posts and re-enforcement bolt plate, a wedge shaped pinblock extending from side to side of the plate on the back of the plate and above the soundboard, flanges extending from the plate on the front side of the plate to strengthen the plate, said flanges extending continuously along the top of the plate from side to side and partially along the upper sides of the plate, said lateral flanges having openings for screws to at-

tach the flanges to a rim or the upper casing of the piano.

10. In a piano, the combination of a horizontal piano case of general grand piano contour, a vertical string plate, a vertical soundboard, both having a transverse length substantially equal to the width of said case, means on the string plate and soundboard to secure the same to the sides of the case to divide the case into a forward and a rearward resonance chamber, said string plate and soundboard being undercut at the bottom of the case, the undercut portions of the string plate and soundboard extending vertically below the bottom of the case, with the sides of the undercut portions of the string plate and soundboard spaced inwardly from the lateral walls of the case, and spaced inwardly from the front and rear walls of the case, bass strings extending from the lower right hand side of the string plate to the upper left hand side of the string plate, midsection strings extending from the lower left hand side of the string plate to the upper right hand side of the string plate, treble strings at the upper right hand side of the string plate, a wedge shaped tuning pin block at the upper end of the soundboard, tuning pins arranged in said block, from one edge of the block to the other edge, the tuning pins for the upper ends of the bass strings being at the narrower end of said block, and a bridge for the bass strings adjacent said narrower end, whereby the upper ends of the bass strings, extend over a lateral extension of the string plate formed by the undercut, and to near the upper edge of the string plate, and the largest soundboard area for said bass strings, is obtained relative to the vertically shortened string plate.

11. In a piano, having a vertically disposed soundboard with a vertically disposed string plate with strings, the combination of a horizontally disposed case having a horizontal bottom and a top parallel therewith with vertical enclosing walls, including front, rear and side walls connecting the bottom with the top, enclosing the upper part of the vertical soundboard, plate and strings, and the hammers, said case extending

forwardly and rearwardly of said upper parts forming resonance chambers, one in the front enclosing all of the hammers, and one in the rear of the soundboard horizontally of the hammer of the piano action, and a vertically disposed casing having front, rear, side and bottom walls with an open top, enclosing the remaining and lower part of the soundboard, plate and strings, said vertical casing extending from the bottom of horizontal said case with the front and rear of the vertical casing spaced inwardly from the front and rear walls of said horizontal case, the interior of the vertical casing at the rear of the soundboard communicating with the resonance chamber of the horizontal case at the rear of the soundboard and forming with the laterally extending horizontal resonance chamber an inverted L, and the interior of the vertical casing at the front of the soundboard communicating with the resonance chamber of the horizontal case at the front of the soundboard.
